ROLL POLISHER

Archibald D. Evans, Warren, Ohio, assignor to
 The Wean Engineering Company, Incorporated,
 Warren, Ohio, a corporation of Ohio

Application May 24, 1932, Serial No. 613,168

5 Claims. (Cl. 51—253)

My invention relates to an apparatus for continuously polishing the surfaces of the rolls of a hot mill in order to preserve a smooth rolling surface thereon.

It is well known that the process of rolling metal, especially the rolling of thin gauge material, such as sheets and tin plate, is accompanied by the formation of oxide either on the rolls themselves which operate at high temperatures, or on the metal being rolled, from which it is transferred to the rolls, or both. The oxide formed during the hot rolling produces a roughness in the surface of the rolls which is cumulative and very soon prevents the turning out of material of satisfactory quality. It then becomes necessary to shut down the mill for the purpose of redressing or polishing the rolls. Heretofore, this has usually been done manually and requires a stoppage of the mill for about five minutes, twice during every hour of operation. The stoppage of production, however, is not the only objectionable feature of manual polishing. It is impossible to obtain a uniform reduction in the surface of the rolls and the result generally is excessive scouring in certain areas. When operation is resumed, therefore, the quality of the product is not good because of the roughness of the rolls resulting from manual polishing. The roll surfaces, therefore, are practically never in good condition, being roughened either by the repeated rolling of bits of oxide or by the polishing operation itself, which is intended to smooth the surface but actually introduces additional roughness because of the uncertainty of manual polishing.

The necessity for excessive scouring of the rolls during manual polishing will be obvious from the fact that during a thirty minute operating period, the rolls turning at the usual rate, will have made about nine hundred revolutions. For the greater part of this time, the rolls are bearing one on the other, although they are separated when metal passes therebetween. While the rolls are in contact, any bits of scale from the roll surface or the material being rolled will be picked up by one roll, carried around, transferred to the other roll and carried around it repeatedly, roughening the surface of both rolls at each turn. The excessive and cumulative roughness thus produced makes it necessary to scour the rolls pretty deeply to remove the pits and rough spots.

Although it has been proposed heretofore to provide mechanical polishing means, no such means with which I am familiar has been suc-

cessful as a practical matter. The difficulties with prior mechanical polishers have been that they interfere with the orderly operation of the mill, prevent easy changing of the rolls, are so close to the housings and mill spindles as to be in great danger in case of breakage of the roll, and have not been protected from the hot grease falling from the necks of the rolls, which is thus transferred to the material being rolled. Prior mechanical polishers, furthermore, have not been adjustable as to the degree of polishing effort applied and have not permitted the application of continuous polishing to restricted or localized areas along the roll barrel. They have also been characterized by difficulty in changing polishing stones in case of breakage and have prevented manual polishing where necessary at infrequent intervals to remove very deep pits from the roll surfaces.

I have invented a continuous roll polisher which successfully overcomes the disadvantages of prior devices and is also characterized by additional features of novelty. In accordance with my invention, I mount a polishing stone for each roll of a two-high hot mill on a bar or shaft which is slidably supported in bearings mounted in the mill housings. Adjustable means are provided for applying torque to the bars to force the stones against the roll surfaces, as well as means for continuously reciprocating the stones throughout the full width of the mill or a limited portion thereof only. The means for reciprocating the stones includes racks and pinions designed to permit rotation of the polisher bars as well as axial movement thereof. The polished bars are reciprocated by a reversing motor, and a reversing limit switch capable of a plurality of adjustments controls the motor for full width reciprocation of the polisher or operation thereof in a restricted zone. For a complete understanding of the invention, reference is made to the accompanying drawings illustrating a present preferred embodiment of the invention, it being understood, of course, that various changes in the described embodiment may be made within the scope of my broader claims. In the drawings:—

Figure 1 is a side elevation, with parts broken away, showing a mill having the invention applied thereto;

Figure 2 is an end elevation;

Figure 3 is a plan view;

Figure 4 is a sectional view taken along the line IV—IV of Figure 1;

Figure 5 is a partial end elevation to enlarged

scale showing in greater detail the mechanism for causing the polishing stones to engage the roll surfaces with the necessary pressure;

Figure 6 is a side elevation of the polisher bars showing the stones associated therewith;

Figure 7 is a partial sectional view along the line VII—VII of Figure 3;

Figure 8 is an enlarged side elevation of a holder for the polishing stones; and

Figure 9 is a partial view of the right-hand end of the mill as shown in Figure 1, the polisher bars appearing in section, showing the application of manual means for forcing the polishing stone against the roll surface.

Referring now in detail to the drawings, a mill 10 comprises housings 11 and 12 slidably mounted on bed rails 13. The housings 11 and 12 are provided with windows 14 in which are mounted bearings (not shown) for the mill rolls 15 and 16.

At one side of the windows 14 in the housings, a recess 17 is formed to receive a bearing plate 18 having slide bearings 19 for upper and lower polisher bars 20 and 21. The plates 18 are secured to the housings by screws 22 and the bearings are preferably disposed symmetrically above and below the horizontal plane passing through the bite of the rolls.

The bars 20 and 21 have arcuate teeth 23 formed thereon covering about half their circumference and extending along the axes of the bars for only a portion of their length. The toothed portions of the bars are separable from the remainder thereof to which they are connected by screw joints. Polishing stones 24 are mounted on the bars 20 and 21 in holders 25. As shown in Figure 8, each of the holders comprises a sleeve 26 adapted to be secured to the bars by screws 27, and a box 28 trunnioned on the sleeve 26 by a pin 29. A screw 30 extending through a side of the box 28 secures the stone therein.

The ends of the bars 20 and 21 are counter-bored and tapped. Extension sections 20a and 21a may thus be screwed into the ends of the bars in case the mill is set up for a greater width of material, necessitating a wider traversing movement of the polishing stones to cover the entire roll surface. Bearing brackets 31 are mounted on the ends of the bars 20 and 21 and the extensions, if any. These brackets are illustrated best in Figures 5 and 6 and are supported on end rods 32 which screw into the ends of the bars in the same manner as the extension members 20a and 21a. The brackets 31 have arms 33 projecting away from the rolls at the level of the axis of the bars 20 and 21. Discs 35 are keyed to the reduced ends of the end rods 32. Chains 36, including a link 37 secured to the discs, pass around the periphery thereof. One end of each of the chains extends to an adjustable spring sustained terminal 38. The other end of each of the chains engages an adjustable terminal 39. The spring terminals 38 are slidably carried in fingers 40 projecting from the arms 33. Fingers 41 also extend outwardly from the arms 33 to provide a support for the terminals 39, which may be adjusted by means of pin connections 42. It will be apparent from an inspection of Figure 5 that by adjusting the terminals of the chains 36, the torque on the bars 20 and 21 may be varied to cause the stones 24 to bear on the roll surfaces with different degrees of pressure. Handles 43 on the terminals 39 and adjusting nuts 44 on the terminals 38 facilitate the variation of the pressure exerted by the polishing stones.

In order to give the polishing stones a traversing movement axially of the rolls 15, 16, I mount a gear box 45 on the housing 11. Shafts 46 journaled in anti-friction bearings 47 in the gear box 45 are provided with throat pinions 48 and driving gears 49. The throat pinions mesh with the circumferential teeth on the bars 20 and 21 so that, in effect, there is provided a pair of racks and pinions such that the rack member has a limited rotary movement relative to the pinion. A drive shaft 50 is also journaled in the box 45, in bearings 47, and is provided with a pinion 51 meshing with the gears 49. It will be obvious that rotation of the shaft 50 in one direction causes simultaneous axial movement of both the bars 20 and 21 in the same direction and to the same extent. Reverse rotation of the shaft 50 likewise reverses the axial movement of the bars 20 and 21.

The shaft 50 is driven through a universal spindle 52 and a speed reducer 53, by a motor 54. The low speed shaft of the reducer 53 drives the high speed shaft of a reducer 55 and the low speed shaft of the reducer 55 actuates a rotary limit switch 56 for controlling the motor 54. The reducers 53 and 55, the motor 54 and the limit switch 56 are mounted on a common base 57. A removable cover 58 shown in dotted lines in Figure 2 may be placed on the base 57 to protect the apparatus supported thereon. The limit switch 56 may be of standard design and is effective, cooperating with suitable relays and contactors, for stopping and reversing the motor 54 when the polishing stones have reached the limits of their travel. Preferably, the switch 56 is adjustable so that different ranges of travel of the polishing stones can be utilized. Thus, if it is desired to remove a deep mark from one of the rolls, the limit switch can be adjusted so that the polishing stones will reciprocate back and forth between limits only a short distance on either side of the mark.

Figure 9 illustrates how additional pressure can be brought to bear on the polishing stones. A strap wrench 59 can be applied to either of the bars 20, 21, preferably adjacent the mill housing 12 and, by appropriate manipulation of the wrench, additional torque can be applied to the polisher bars so that the stones will engage the rolls with greater pressure. This feature is especially useful in grinding down deep impressions in the roll surfaces. Normally, of course, the stones are urged against the roll surfaces only by the pressure of the spring terminals 38.

The invention described is obviously characterized by numerous advantages, both over the prior practice of manually polishing mill rolls and also over mechanical polishers known to the prior art. In the first place, by operating the polisher of my invention continuously or substantially so, the roll surfaces are always maintained in good rolling condition and shutdowns or stoppages of the mill for the purpose of restoring a smooth surface on the rolls are avoided. The polishing operation, therefore, does not interfere with the normal mill operation and permits high production speeds to be maintained continuously. The apparatus can be readily removed for changing rolls by releasing the holder sleeves 26, disconnecting the driving spindle 52 and unscrewing the untoothed portions from the toothed portions of the bars 20, 21. The untoothed portions of the bars may then be withdrawn from the mill housings.

In addition to the foregoing advantages, the

operating mechanism for the polisher is largely disposed remote from the housings and the mill spindle so as to avoid damage in case of roll breakage. The polisher bars, furthermore, are 5 protected by their slide bearings from the grease falling from the roll necks. The bars, therefore, cannot carry such drippings on to the material being rolled. The polishing pressure exerted on the rolls by the stones can very readily be adjusted, as previously explained, and it is also possible to vary the area in which polishing is effected by varying the contacts of the limit switch. The 10 polishing stones themselves can be readily replaced in case of breakage or wear and manual polishing can be resorted to in case of deep marks, if desired. The throat type pinions driving the polisher bars are effective to give axial movement thereto without preventing rotation thereof about their axes. The stone holder, being trunnioned to the reciprocating polisher bars, can 15 shift so that the stone adapts itself to the position of maximum contact with the roll surface.

Although I have illustrated and described herein but one embodiment of the invention, it will be obvious that numerous changes in the embodiment described may be made without departing from the spirit of the invention or the scope of the appended claims.

I claim:

30 1. A roll polisher for a rolling mill including a pair of housings having work-engaging rolls journaled therein, comprising bearings in said housings, a pair of polisher bars supported in said bearings for transverse sliding movement, means carried by said bars for holding polishing

stones against the rolls, means for exerting a torque on said bars to force the stones against the rolls, and means for reciprocating said bars including throat type pinions and circumferential rack teeth on said bars engaged by said pinions.

80

2. A roll polisher for rolling mills, comprising a bar adapted to extend transversely of the mill, a polishing stone mounted on the bar for engaging one of the mill rolls, a disc secured to said bar, a bracket on the bar, a chain connected to said disc for exerting a torque on the bar, and a yielding anchorage on said bracket for one end of said chain.

85

3. A roll polisher for rolling mills including a shaft adapted to extend transversely of the mill, a polishing stone mounted on the shaft for engaging a mill roll, means for exerting a torque on the shaft to force the stone against the roll, and means for reciprocating said shaft comprising circumferential rack teeth thereon and a pinion meshing therewith.

90

4. A roll polisher for a rolling mill, comprising a shaft parallel to the axes of the mill rolls, a polishing stone mounted on the shaft for engaging one of the rolls, means exerting a torque on 100 said shaft tending to rotate it about its own axis, and means for reciprocating the shaft including circumferential rack teeth thereon and a pinion having arcuate teeth meshing with said rack teeth.

105

5. The apparatus set forth in claim 2 characterized by the fact that the other end of said chain is provided with retracting means, and securing means for the retracting means.
